The ornamental design for a tricycle steering wheel, as shown and described.

DESCRIPTION

FIG. 1 is a perspective view of a tricycle steering wheel, shown in position of use on a tricycle, which is shown in broken lines for illustrative purposes only and forms no part of the claimed design.

FIG. 2 is an enlarged top view of the tricycle steering wheel. FIG. 3 is an enlarged lower view of the tricycle steering wheel.

FIG. 4 is an enlarged front view of the tricycle steering wheel. FIG. 5 is an enlarged rear view of the tricycle steering wheel; and,

FIG. 6 is an enlarged right view of the tricycle steering wheel, the left view is symmetric.
